UNITED STATES PATENT OFFICE.

HENRY P. CLARK, OF INDEPENDENCE, MISSOURI.

DESIGN FOR A GEAR-WHEEL BOXING FOR CLOTHES-WRINGERS.

SPECIFICATION forming part of Design No. 34,377, dated April 16, 1901.

Application filed March 19, 1901. Serial No. 51,948. Term of patent 14 years.

To all whom it may concern:

Be it known that I, HENRY P. CLARK, a citizen of the United States, residing at Independence, in the county of Jackson and State 5 of Missouri, have invented and produced a new and original Design for a Gear-Wheel Boxing for Clothes-Wringers, of which the following is a specification.

My invention relates to gear-wheel boxings 10 for clothes-wringers; and my object is to produce a new and original design for the same which is both useful and ornamental.

In the accompanying drawings, Figure 1 is 15 a perspective view. Fig. 2 is a front view, and Fig. 3 is a side view.

The leading or material feature of the design consists in a vertically-elongated hollow body, open at its rear side and provided with flanges in the plane of its rear side and with 20 a slot in one of its side walls.

Minor features of the design reside in the 25 rounding corners of the body and flanges, in the approximately V-shaped horizontally-extending grooves centrally of the side walls, in an opening in its front side about centrally of the lower half thereof, in the holes in the

flanges, and in a slot in the opposite side wall similar to the one above referred to.

Referring to the drawings in detail, 1 designates the elongated hollow body, open at its 30 rear side, 2 the flanges at the rear side thereof, and 3 the holes in said flanges.

4 designates the opening in the front side of the body, and 5 the slots in the side walls.

6 designates the rounding corners of the 35 body; 6^a, the rounding corners of the base-flanges; 7, the approximately V-shaped grooves in the side walls, and 8 the slot in the opposite side wall.

Having thus described the invention, what 40 I claim, and desire to secure by Letters Patent, is—

The design for a gear-wheel boxing for 45 clothes-wringers, substantially as herein shown and described.

In testimony whereof I affix my signature in the presence of two witnesses.

HENRY P. CLARK.
